Patented June 20, 1961

190,679

NAUTICAL CHOCK

Alexis de Sakhnoffsky, Grand Rapids, Mich., assignor
to Attwood Corporation, a corporation of Michigan

Filed Apr. 13, 1960, Ser. No. 60,175

Term of patent 14 years

(Cl. D54—11)

Fig. 1

Fig. 2

Fig. 3

Fig. 4

FIG. 1 is a front perspective view taken from one side of a nautical chock showing my new design;

FIG. 2 is a side elevational view thereof, the opposite side being substantially the same;

FIG. 3 is a top plan view thereof; and

FIG. 4 is an enlarged fragmentary view of one side thereof, taken slightly in perspective, showing the front end of the nautical chock.

I claim:

The ornamental design for a nautical chock, substantially as shown and described.
